RAIL FLAW DETECTOR MECHANISM

Harcourt C. Drake, Hempstead, N. Y., assignor to
Sperry Products, Inc., Brooklyn, N. Y., a corporation of New York

Application March 23, 1935, Serial No. 12,715

11 Claims. (Cl. 175—183)

This invention relates to rail flaw detector mechanisms and more particularly to the type of mechanism employed on the Sperry rail flaw detector cars. These cars operate on the fundamental principle of sending current of high amperage through the rail to establish an electromagnetic field and then exploring said field for irregularities caused by the presence of flaws within the rail. The exploring or detector means 5 comprises one or more sets of inductive means arranged in tandem along the rail. It was discovered that if coils extending substantially across the railhead were employed, centrally located fissures were sometimes missed because 10 the diminution of flux at one point was counterbalanced by the increase in flux at other points across the rail head and a coil extending substantially across the rail head integrated the flux so that apparently there was no different total flux 15 at a place of flaw than at a region without flaw. In order to obviate this objection a plurality of sets of coils were employed, each set coating with only a portion of the rail head width so that one set of coils detected fissures nearer the gauge side 20 while the other set detected fissures nearer the outside of the rail head. The coils of each set are balanced and in opposition, and the coils of one set were arranged to alternate with the corresponding coils of the other set whereby a multiplied output was obtained in response to a flaw. It has been customary to mount all of said coils 25 within a housing which was supported on a carriage at a constant distance above the rail surface. This construction, however, was found to be subject to picking up irregularities in flux due 30 to surface defects such as burns caused by the slipping of locomotive wheels and which were not internal defects. It was found that if each coil could be so mounted that it followed the contour 35 of the rail surface and could at all times maintain its parallelism with said surface, such surface defects did not affect the detector means and therefore caused no confusion with real internal defects. It has therefore been proposed that 40 each coil be mounted individually as shown in applicant's Patent No. 1,960,968 granted May 29, 1934, but this necessitated a complicated construction and resulted in error because one coil of a balanced pair could move laterally with respect 45 to the other coil with a result that induced E. M. F., thus giving an indication of flaw where none actually existed.

It is the object of the present invention to provide a mounting for a plurality of sets of coils 50 which will permit each coil of each set to main-

tain its axis at all times at a fixed distance above the rail surface by following the contour of the rail surface and at the same time prevent lateral movement of one coil of a balanced pair relative to the other coil.

Further objects and advantages of this invention will become apparent in the following detailed description thereof.

In the accompanying drawing, Fig. 1 is a side elevation of a portion of a Sperry 10 rail flaw detector car showing my invention applied thereto.

Fig. 2 is an enlarged side elevation of the detector mechanism and its mounting.

Fig. 3 is a plan view of the detector mechanism 15 of Fig. 2.

Referring to Fig. 1, there is shown a portion of a Sperry rail flaw detector car adapted to travel along the rails to be tested. Current is supplied to the portion of the rail under test from a generator G within the car which supplies current to the rail R by means of sets of brushes 11 and 12. Said brushes 11 and 12 are carried by a current brush carriage 15, said carriage being supported from the car body 10 by means such as 20 cables 16 and springs, not shown, which normally maintain the current brush carriage in raised or ineffective position. When it is desired to lower said carriage into engagement with the rail, fluid pressure such as compressed air is supplied 25 to cylinders 17 to depress pistons 18 operating therein, said pistons being connected to the current brush carriage so that said carriage is lowered against the action of the retractile springs. The current brush carriage may be 30 adapted to ride along the rail on means such as flanged wheels 19.

The electromagnetic field surrounding the rail is uniform as long as there are no flaws. When flaws occur there is a distortion of the electromagnetic field in the region of the flaw and such distortions are designed to be detected by induction means which may comprise a plurality of pairs of opposed induction coils 20, 20', each of said pairs of induction coils being supported in a 40 housing 21, 21'. Said housings are designed to be supported on detector carriage 22 in a manner to be hereinafter described and said detector carriage is in turn supported on the current brush carriage for movement independent thereof by 45 means such as loose-fitting bolts 23 and springs 24 constituting limited universal joints. The detector carriage may be supported on the rail surface by means such as rollers 25. It will be seen that each pair of coils 20 and 20' coacts 50

55

with respective widths of the railhead, one co-
acting mainly with the portion of the rail head
near the gauge side and the other with the por-
tion of the rail head near the outside. The coils
5 of each pair are balanced and oppositely wound,
and the coils of one pair alternate with the cor-
responding coils of the other pair. It will now
be seen that as the car travels along the rail each
pair of inductive coils 20, 20' will normally cut
10 a constant number of lines of force as long as
the rail is free from defect, since the electro-
magnetic force is undistorted. When a region of
flaw is encountered, one of the coils of each pair
will cut a different number of lines of force and
15 there will be generated a differential E. M. F.
which after being amplified may be caused to
operate indicating means, such as pens operating
on a chart, and rail marking means, such as a
paint gun. The alternating arrangement of the
20 coils provides a larger response to a flaw than
could be obtained by either pair of coils sepa-
rately by reason of the fact that the impulses
generated by the pairs of coils in this arrange-
ment reinforce each other.

25 The accuracy of the detector mechanism de-
pends upon maintaining the axis of the coils at
all times at a fixed distance above the rail sur-
face. For this reason it is highly desirable that
some provision be made whereby the coils may
30 follow the contour of the top surface of the rail
since a burn or similar defect on the surface
will tend to increase the distance of the axis
from the rail surface and thus cause the coils
35 to cut a different number of lines of force than
normally to induce an E. M. F. and give a false
indication of flaw. To permit the coils to follow
the contour of the rail surface without compli-
cating the mechanism whereby the housings 21
40 and 21' are supported on the detector carriage
22, I have provided for a mounting of each hous-
ing 21 and 21' on a pivotal axis formed by bear-
ings 30, 30' on the upper surface of the housings
21 and 21'. Bell-cranks 32, 32' are pivotally
45 journaled at 34, 34' on the detector carriage 22,
and are journaled in bearings 30, 30' by means
of shafts 31, 31'. The bell-cranks 32, 32' are
normally pressed downwardly by means such as
springs 36, 36' or other equivalent resilient means
50 connected to the detector carriage and to the up-
per ends of the bell-cranks, said springs tending to
maintain the housings 21, 21' in depressed position
in engagement with the rail, but permitting said
housings to adjust themselves to surface irreg-
ularities. The housings 21, 21' may ride upon
55 the rail either on sleds 39, or upon rollers as
shown in applicant's Patent No. 1,960,968, granted
May 29, 1934.

By the construction described above it will be
seen that each housing 21, 21' is free to pivot
60 about its axis 30, 30' and about the axes 34, 34',
so that each end of the housing may follow the
contour of the rail into each hollow or elevated
portion, as case may be, and thus maintain the
axis of the coil a constant distance above the
65 portion of the rail which it is testing, irrespec-
tive of the movements of detector carriage 22.
At the same time, it is impossible for one coil of
a pair to move laterally relative to the other coil,
which movement would generate an impulse like
70 that of a flaw, by reason of the mounting of each
balanced pair in a housing which is so mounted
that both ends thereof are constrained to move
laterally to the same degree. Stops 41 and 41'
75 may be fixed to the carriage 22 in the path of
movement of the bell-crank to limit the down-

ward movement of the housings with respect to
the carriage 22 when the current brush carriage
is elevated and when open spaces in the rail,
as at switches, are passed over. It will be seen
further that the housings 21 and 21' are so formed
5 that the alternating and overlapping arrange-
ment of the corresponding coils of the two pairs
is possible. This formation consists in cutting
out portions 40, 40' and fitting the housings into
one another. Thus, two important results are 10
obtained. First, the alternating and overlapping
arrangement of coils is made possible, whereby
stronger impulses are obtained at the flaws; and,
second, each pair of balanced coils is contained
15 in its own housing and the housing so mounted
that it is impossible for one coil of a pair to
move laterally with respect to the other coil.

In accordance with the provisions of the patent
statutes, I have herein described the principle
and operation of my invention, together with the 20
apparatus which I now consider to represent the
best embodiment thereof, but I desire to have it
understood that the apparatus shown is only ill-
lustrative and that the invention can be carried
out by other equivalent means. Also, while it 25
is designed to use the various features and ele-
ments in the combination and relations described,
some of these may be altered and others omitted
without interfering with the more general results
outlined, and the invention extends to such use. 30

Having described my invention, what I claim
and desire to secure by Letters Patent is:

1. In a rail flaw detector car, flaw responsive
means comprising a plurality of sets of inductive
means, a housing for each set, each of said hous- 35
ings having means engaging the rail, a support
for said housings, and means whereby each of
said housings is pivotally mounted on said sup-
port for movement about an axis transverse to
the rail, said axis being positioned intermediate 40
the inductive means in each housing.

2. In a rail flaw detector car, flaw responsive
means comprising a plurality of sets of inductive
means, a housing for each set, each of said hous- 45
ings having means engaging the rail, a support
for said housings, and means whereby each of
said housings is pivotally mounted on said sup-
port for vertical movement relative to said rail
and said support, and means whereby each of 50
said housings is pivotally mounted for rocking
movement about an axis transverse to the rail.

3. In a rail flaw detector car, flaw responsive
means comprising a plurality of sets of inductive
means, a housing for each set, each of said hous- 55
ings having means engaging the rail, a support
for said housings, and means whereby each of
said housings is pivotally mounted on said sup-
port about an axis transverse to the rail for ver-
tical movement relative to said rail and said sup- 60
port, and means whereby each of said housings
is pivotally mounted for rocking movement about
an axis transverse to the rail.

4. In a rail flaw detector car, flaw responsive
means comprising a plurality of sets of inductive
means, a housing for each set, each of said hous- 65
ings having means engaging the rail, a support
for said housings, and means whereby each of
said housings is pivotally mounted on said sup-
port about an axis transverse to the rail for ver-
tical movement relative to said rail and said sup- 70
port, and means whereby each of said housings
is pivotally mounted for rocking movement about
an axis transverse to the rail, said last-named
axis being positioned between the inductive
means in each housing. 75

5. In a rail flaw detector car, flaw responsive means comprising a plurality of sets of inductive means, a housing for each set, each of said housings having means engaging the rail, a support for said housings, and means whereby each of said housings is pivotally mounted on said support, said last-named means comprising a plurality of links, each link pivotally connected at one end to said support and pivotally connected at the other end to one of said housings. 5
6. In a rail flaw detector car, flaw responsive means comprising a plurality of sets of inductive means, a housing for each set, each of said housings having means engaging the rail, a support for said housings, and means whereby each of said housings is pivotally mounted on said support, said last-named means comprising a plurality of links, each link pivotally connected at one end to said support and pivotally connected at the other end to one of said housings. 10
- 15
- 20
- 25
- 30
- 35
- 40
7. In a rail flaw detector car, flaw responsive means comprising a plurality of sets of inductive means, a housing for each set, each of said housings having means engaging the rail, a support for said housings, means whereby each of said housings is pivotally mounted on said support for vertical movement relative to said rail and said support, means whereby each of said housings is pivotally mounted for rocking movement about an axis transverse to the rail, and means for limiting the movement of said housings relative to said support. 25
8. In a rail flaw detector car, flaw responsive means comprising a plurality of sets of inductive means, each set comprising a pair of balanced coils, said coils being arranged so that the coils of one pair alternate with the corresponding coils of another pair, a housing for each pair of coils, a support for said housings, and means whereby each of said housings is pivotally mounted on said support. 30
9. In a rail flaw detector car, flaw responsive means comprising a plurality of sets of inductive means, each set comprising a pair of balanced coils, one pair cooperating principally with the gauge side of the rail head and the other pair cooperating principally with the outside of the rail head, said coils being arranged so that the coils of one pair alternate with the corresponding coils of another pair, a housing for each pair of coils, a support for said housings, and means whereby each of said housings is pivotally mounted on said support. 35
10. In a rail flaw detector car, flaw responsive means comprising a plurality of sets of inductive means, each set comprising a pair of balanced coils, one pair cooperating principally with the gauge side of the rail head and the other pair cooperating principally with the outside of the rail head, the portions of the rail head with which said pairs of coils cooperate overlapping, said coils being arranged so that the coils of one pair alternate with the corresponding coils of another pair, a housing for each pair of coils, the portions of the rail head with which said housings cooperate overlapping, a support for said housings, and means whereby each of said housings is pivotally mounted on said support. 40
11. In a rail flaw detector car, flaw responsive means comprising a plurality of sets of inductive means, each set comprising a pair of balanced coils, said coils being arranged so that the coils of one pair alternate with the corresponding coils of another pair, a housing for each pair of coils, and a support for each of said housings including means for constraining said housings to vertical movement. 45

HARCOURT C. DRAKE. 40
